CLAIM

The ornamental design for an orthopedic volar bone plate, as shown and described.

DESCRIPTION

FIG. 1 is a top perspective view of an orthopedic volar bone plate showing my new design;

FIG. 2 is a top plan view thereof;

FIG. 3 is a back elevation view thereof;

FIG. 4 is front elevation view thereof;

FIG. 5 is a left side elevation view thereof;

FIG. 6 is a right side elevation view thereof;

FIG. 7 is a top perspective view of another embodiment of an orthopedic volar bone plate showing my design;

FIG. 8 is a top plan view thereof;

FIG. 9 is a back elevation view thereof;

FIG. 10 is front elevation view thereof;

FIG. 11 is a right side elevation view thereof; and,

FIG. 12 is a left side elevation view thereof.

The broken lines are for illustrative purposes only and form no part of the claimed design. It will be understood that the bottom of the orthopedic volar bone plates are plain and unornamented.
